CLAIM

The ornamental design for a pool fill valve, as shown and described.

DESCRIPTION

FIG. 1 is a perspective view of the pool fill valve of the present invention showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left end view thereof;

FIG. 7 is a right end view thereof; and,

FIG. 8 is a front elevational view thereof with the dotted lines depicting solely environmental structure and forming no part of the claimed design.
